UNITED STATES PATENT OFFICE

PETER O. BORGESON, OF MIAMI, FLORIDA

WINDOW OPENER

Application filed May 9, 1930. Serial No. 451,095.

This invention relates to window openers and has for an object to provide a device adapted to open a window such as a casement window and permit of the window being reversed so that the outside of the window pane may be washed from the inside of the room. A further object is to provide a casement window opener which will operate to automatically lock the window in full open or closed positions as well as in an oblique open position.

A still further object is to provide a casement window opener which will be operated from inside the window casing and which will be formed of a few strong and durable parts that will be inexpensive to manufacture and will not easily get out of order.

A still further object is to provide a window opener in which the operating lever and the locking parts associated therewith will be positive in action to open and close the window and will be carried by a novel housing which may be easily and quickly attached to the window casing without alterations thereto.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a cross-sectional view of a casement window equipped with my improved window opener and also showing the hinges which attach the window to the window casing;

Figure 2 is a cross-sectional view similar to Figure 1 but showing the window open and reversed to permit of the outside of the pane being washed from inside the room;

Figure 3 is a fragmentary plane view of the operating lever and locking devices with the cover of the housing removed;

Figure 4 is a detail sectional view taken

on the line 4—4 of Figure 3 and showing the mechanism in locked position,

Figure 5 is a detail sectional view similar to Figure 4 and showing the mechanism in unlocked position,

Figure 6 is a fragmentary plane view showing the locking catch for holding the connecting link in alignment with the operating lever,

Figure 7 is a fragmentary front elevation showing the hinge for attaching the casement window to the window casing,

Figure 8 is an end elevation of the hinge showing the grip of the locking latch in closed position, and

Figure 9 is a detail sectional view taken on the line 9—9 of Figure 8.

Referring now to the drawings in which like characters of reference designate similar parts in the various views, 10 designates a window casing, 11 the frame of a casement window, the window having the usual glass pane 12, and 13 designates in general a window screen which as usual in casement window construction is mounted in the window casing inside the window.

In carrying out the preferred embodiment of the invention, I preferably use hinges of the general type described in my co-pending application filed of even date herewith, said hinges each comprising leaves 14 and 15 hinged together as shown at 16. The leaf 15 is rigidly secured to the casement window frame 11 and the hinge 14 is hinged as shown at 17 to a securing plate 18 which is rigidly secured to the window casing 10. The hinge 14 is provided with a locking lug 19 which is engaged by a locking latch 20, best shown in Figure 9 as pivoted on a flange 21, carried by the leaf 15. The latch is provided with a grip 22 which lies flush with the face of the flange and projects into a thumb notch 23.

The leaves 14 and 15 normally lie flat against each other to permit of the window being opened in the usual manner to the position shown in dotted lines in Figure 1. However, the leaves are adapted to open as best shown in Figure 2 when it is desired to reverse the window for washing the inside

of the window pane or for permitting the window to remain open in an oblique position to provide better ventilation.

The operating mechanism for opening and closing the window comprises in general a lever arm 24 which is terminally slotted as shown at 25 to receive the pivot pin 26 of a connecting link 27. The connecting link is terminally equipped with an eye 28 which is pivoted to the connecting link as shown at 29 and encircles a guide rod 30, the ends of which are fixedly secured preferably by screws 31 to the lower horizontal rail of the casement window sash.

When the pivot pin 26 of the connecting link is disposed at the inner end of the slot 25 in the lever arm the link extends in alignment with the lever arm as best shown in Figure 1 and is detachably secured in this position by means of a catch 32 which is pivoted on the lever arm as shown at 33, and is terminally equipped with a lip 34 as best shown in Figure 6, which lip engages in registering slots formed in the lever arm and connecting link.

The lever arm 24 is operated by means of an operating lever 35 which is operatively connected to the lever arm as will herein-after be fully described. When the operating lever 35 is rocked transversely of the window sill the lever arm 24 and connecting link 27 will be rocked to the position shown in dotted lines in Figure 1, thereby sliding the eye 28 longitudinally of the guide rod 30 and swinging the window to full open position. Should it be desired to reverse the window to the position shown in Figure 2 it is necessary to disengage the catch 32 and move the connecting link 27 outwardly so that the pivot pin 26 thereof is disposed at the outer end of the slot 25.

The above described locking latches 20 of both the upper and lower hinges are first released to permit of the leaves of the hinges opening. The connecting link is now shoved outwardly on the lever arm until the pivot pin 26 thereof engages in the outer end of the slot 25. Thereupon the operating lever 35 may be rocked in the reverse direction from that used to open the window, and during this movement as best shown in Figure 2, the connecting link 27 will be moved to extend at a right angle to the lever arm 24 and during continued movement of the parts the inner and outer leaves 14 and 15 of the hinges will be opened and will reverse the window so that the outside of the window pane faces inwardly.

In order that the window will be automatically locked in an angular open position and also when closed, a locking mechanism is employed and comprises an arcuate rack 36 which is rigidly secured to a base plate 37 the latter being preferably secured to the window sill by screws 38. A fork 39 as best shown in

Figures 3, 4 and 5 is terminally equipped with teeth 40 adapted to engage between the teeth 41 of the rack 36.

The fork 39 is pivoted on the base plate by a pivot pin 42 and is pressed downwardly by a helical spring 43 which surrounds the pivot pin and is confined between the fork and a cap or cover plate 44 which is of the general shape shown in Figure 1 and houses the fork and is mounted on the pivot pin 42 to turn thereon as a unit with the fork. The fork is provided at its rear end with lips 45 to receive the end of the above mentioned operating lever 35. When the operating lever 35 is depressed obviously the lever will serve to tilt the fork on the pivot pin 42 and disengage the teeth 40 thereof from between the arcuate rack teeth 41 on the base plate 27 as best shown in Figure 5. The lever 35 is now free to be rocked to open or close the window and upon the lever being released the spring 43 automatically depresses the fork 39 and engages the teeth thereof between adjoining teeth of the arcuate rack whereby the parts are locked against movement.

The operating lever 35 is provided with a longitudinal slot 46 which receives a pin 47 whereby the lever may be slid forwardly underneath the lips 45 of the fork to connect these parts or may be slid rearwardly so that the end of the lever is disengaged from the leaves of the fork whereupon the lever may be rocked laterally to normally extend longitudinally of the window sill as best shown in Figure 1. By referring to Figure 3 it will be seen that the operating lever arm 27 is secured by screws 48 in a socket member 49 which is secured as shown in Figures 4 and 5 to the cover plate 44 by means of a screw 50. The socket member is formed integral with a plate 51 which is provided with an opening to pivotally receive the pivot pin 42 above described and extends underneath the above described fork 39 to the outer end of the cover plate where it is secured to the latter by means of the pin 47 above described and moves as a unit with the cover plate 44.

It will thus be obvious that the cover plate 44, socket member 49, plate 51 integral therewith, and the fork 39 are all moved as a unit on the pivot 42 when the lever 35 is shifted laterally. It will also be obvious that the fork 39 has vertical movement against the pressure of the spring 43 when the lever 35 is depressed to disengage the locking teeth of the fork. The spring depresses said fork to engage said teeth when the lever is released.

It will be observed from the above description that the casement window opening mechanism will operate to automatically lock the window in full open, in closed, or in oblique intermediate open positions, or in reversed position.

It will be further observed that the locking mechanism is operated from inside the

window and is positive in action and that furthermore, the parts for the most part are housed within the casing constituted by the base plate 37 and cover plate 44 which parts 5 may be easily and quickly attached to the window sill without alterations thereof.

It will be pointed out that my improved device as above described is equally applicable to steel casement windows as well as wood 10 casement windows and that such modifications as are necessary to apply the device to steel in lieu of wood fall within the scope of this invention.

Having thus described the invention, I 15 claim:

1. A window opener comprising a guide rail for attachment to a window frame, a lever arm adapted to be mounted on the window casing, said arm being swingable laterally, a connecting link slidably mounted on 20 said lever arm, means for securing said link in adjusted positions on said arm, an eye pivotally connected to said link and slidable longitudinally on said guide rail, and means 25 for operating said lever arm.

2. A window opener comprising a lever arm, a connecting link carried thereby and adapted to be secured to extend longitudinally of said arm, and adapted to be secured to 30 extend at substantially a right angle to said arm, means pivotally connecting said link with said arm, a guide rail adapted to be secured to a window frame, an eye pivotally secured to said link and encircling said guide 35 rail, an operating lever adapted to be mounted on a window casing, and an operative connection between said operating lever and said lever arm for connecting said lever and said arm for movement as a unit.

3. A window opener comprising a lever arm, a connecting link slidably and pivotally connected to said arm and adapted to extend longitudinally of said arm, and adapted to extend transversely of said arm, a catch pivoted 45 on said arm and normally locking said link and said arm in alignment, a guide rail adapted to be connected to a window frame, an eye encircling said guide rail and pivotally connected to the free end of said link, and an operating lever operably connected to said arm and adapted to be mounted upon a window 50 casing.

4. A window opener comprising a lever arm, a connecting link, means slidably and pivotally connecting said arm and said link, a pivoted catch normally holding said arm and said link disposed in alignment, a guide rail adapted to be connected to a window casing, an operative connection between said 60 guide rail and said link, an operating lever, a support for the operating lever adapted to be secured to a window casing, means on said support operatively connecting said lever to said arm, and means carried by said support 65

for automatically locking said lever arm against movement.

5. The combination with a window and a window casing, of hinges connecting said window to said casing, said hinges having 70 leaves adapted to spread apart and permit of said window being reversed to present the outside of the window pane inwardly with respect to the window casing, a guide rail disposed on said window frame, an operating lever arm adapted to be mounted on the window casing, said arm being swingable laterally, a connecting link slidably mounted on said arm, means for securing said link in adjusted positions on said arm, an eye 75 pivotally connected to said link and slidable longitudinally on said guide rail, and means for operating said lever arm.

6. The combination with a casement window and the window casing thereof, of 80 hinges securing said window to said casing, said hinges being adapted to permit of said window being reversed and dispose the outside of the pane inwardly towards the window casing, a lever arm, a connecting link 85 carried thereby, a pivotal connection between said arm and said link, a guide rail secured to the window frame, an eye pivotally connected to said link and encircling said guide rail, an operating lever adapted to be mounted on the window casing, and an operative connection between said operating lever and said lever arm for connecting said lever and said arm for movement as a unit.

7. The combination with a casement window and the window casing thereof, of hinges securing said window to said casing and adapted to permit of the window being reversed to dispose the outside of the window 90 pane inwardly, a lever arm, a connecting link carried thereby and adapted to be secured to extend longitudinally of said arm, said link being adapted to be secured to extend at substantially a right angle to said arm, a pivot pin carried by said link and slidably fitting in a longitudinal groove formed in said arm, an eye pivotally secured to the free end of said link, a guide rail secured to said window frame in horizontal position, said eye encircling said guide rail, an operating lever 95 adapted to be mounted on the window casing, and an operative connection between said operating lever and said lever arm for connecting said lever and said arm for movement as a unit.

8. A window opener comprising a lever arm, a connecting link carried thereby and adapted to be secured to extend longitudinally of said arm, and adapted to be secured at substantially a right angle to said arm, means pivotally connecting said link with said arm, a guide rail adapted to be secured to the window frame, an eye pivotally secured to said link and encircling said guide rail, a base plate adapted to be fixedly secured 100

to a window casing, a cover plate swiveled on the base plate, an operating lever operatively connected to the cover plate for moving the cover plate, a socket member carried by the cover plate and engaging said lever arm, a tilting fork disposed between said cover plate and said base plate and movable therewith as a unit, said base plate being provided with an arcuate series of rack teeth, said fork having teeth normally engaging said rack teeth and holding said lever arm against movement, and an operative connection between said operating lever and said fork for tilting the fork when said lever is depressed to disengage said meshing teeth.

In testimony whereof I affix my signature.
